SCRAPER

Raymond L. Harrison, Albuquerque, N. Mex.

Application March 24, 1933, Serial No. 662,561

22 Claims. (Cl. 37—129)

My invention relates generally to scrapers and more particularly to scrapers of the trailer type, namely, scrapers in which a trailer construction is employed in combination with a tiltable earth carrying means or bowl.

One of the important objects of my present invention is to provide a scraper having an improved automatic tripping mechanism, which greatly facilitates the ease with which a rotary type scraper bowl may be automatically secured against rotation or released to permit rotation.

More specifically, it is an object of my invention to provide an automatic tripping device, as above set forth, which will function with equal effectiveness when the bowl rotates in forward or reverse direction.

Another object of my invention is to provide improved means for adjusting the position of the cutting edge with respect to the wheels of a trailer construction.

A further object of my present invention is to provide a scraper in which the bowl or earth carrying means is provided with a removable bottom, whereby said bowl or scraper may be used with or without a bottom section, as occasion demands.

The foregoing and numerous other objects and advantages will be more apparent from the following detailed description when considered in connection with the accompanying drawings, wherein—

Figure 1 is a side elevational view of a scraper embodying features of my invention, the same being shown in operative association with a fragmentary portion of a tractor, a portion of the scraper bowl being broken away to more clearly disclose the structural characteristics of my improved latching and tripping device;

Figure 2 is a plan view of the device shown in Figure 1;

Figure 3 is a view similar to Figure 1, disclosing the bowl in vertical cross-section and tilted to a digging position;

Figure 4 is a view similar to Figure 1, disclosing the bowl tilted to its carrying position;

Figure 5 is a fragmentary sectional view taken substantially along the line 5—5 of Figure 1;

Figure 6 is a fragmentary side elevational view of a scraper of modified construction in which the bowl or earth receiving means proper is rigidly secured to the draft frame;

Figure 7 discloses another modified form wherein the bell-crank arrangement disclosed in Figures 1 to 6, inclusive, is displaced by a link and side block construction; and

Figure 8 is a fragmentary transverse sectional

view taken substantially along the line 8—8 of Figure 7 to more clearly disclose the structural features of the slide block arrangement.

Referring now to the drawings more in detail, wherein like numerals have been employed to designate similar parts throughout the various figures, it will be seen in Figures 1 to 5, inclusive, that my invention contemplates the provision of a scraper, which includes an earth receiving means or bowl 10, which is pivotally mounted by trunnions 12 on a draft frame 14. I prefer to form the bowl 10 with a bottom section or plate 16, which is removably secured in position through the agency of any suitable means, such as the angle iron 18 shown in Figure 3. In this manner the bowl is rendered adaptable as a bottomless scraper in instances where the work demands such a construction, and when it is used as a bottomless scraper I prefer to insert a blade 20, indicated by dotted lines in Figure 3.

Attention is directed to the strength and rigidity of the bowl 10, which I obtain by providing an inner wall section 22, which is maintained in spaced relation with and secured to the outer casing 24 by means of struts or braces 26. These may be readily welded in position and serve to materially strengthen the bowl. Scrapers of the type disclosed herein are subjected to extreme working conditions in the field. Sometimes they are called upon to shift heavy wet soil, or to dig into very hard soil, and under such circumstances the bowl proper is subjected to severe stresses and strains. By constructing the bowl in the manner just described, these severe heavy load conditions are satisfactorily met. Attention is also directed to the fact that I provide apertures 28 in the side walls of the bowl, which when in registration with companion apertures 28a provided in the draft frame, are adapted to receive a locking pin (not shown) to rigidly secure the bowl and frame against relative movement. This arrangement is preferred when the tiltable or rotary movement of the bowl is not required. When the bowl is used without the bottom section 16, it is very advantageous to secure the bowl against rotation.

The mechanism for effecting rotation or tilting of the bowl 10 includes a hydraulic actuator designated generally by the numeral 30. This actuator includes a cylinder 32 and a piston 34 reciprocably mounted therein. Fluid power is supplied through flexible conduits 36 and 38, which connect through the agency of a manually manipulated valve 40 with a suitable fluid pump 42 driven from the engine of the tractor 44.

When the handle 46 of the valve 40 is moved in one position, the piston 34 will move in one direction, and when shifted to an opposite extreme position, the piston will move in the opposite direction. In a third position, the valve prevents flow of fluid through the conduits 36 and 38 in either direction, thereby locking the piston 34 in position. The specific construction of the valve does not form a part of this invention, and therefore the details thereof are not shown herein. It will suffice to say that an operator positioned on the seat 48 of the tractor 44 may conveniently manipulate the handle 46 to control the position of the piston 34.

Connected to the piston 34 is an actuating bar 50, which is pivotally secured at its outer extremity with a cross bar 52 which extends between a pair of frame members 54. These frame members 54 are pivotally supported by the trunnions 12, and are connected through the agency of extensible links 56 with one arm of a bell-crank 58. These bell-cranks 58 are pivotally supported by the draft frame 14. The rearwardly extending arm of the bell-crank 58 supports an axle or shaft 60 carrying trailer wheels 62. Thus, it will be apparent that when the piston 34 is shifted rearwardly, the bell-crank 58 rotates in a clockwise direction, thereby causing the draft frame 14 to be elevated, as clearly shown in Figure 4. Likewise, when the actuator piston 34 is shifted in the opposite direction, the bell-crank is moved in a counter-clockwise direction, thereby causing the trailer wheels 62 to be elevated to the position shown in Figure 3.

Reference is now made to my improved latching and tripping mechanism, which includes a pair of adjacently positioned rotary latch members 64 and 66, which are mounted on the inner side of each frame member 54, as clearly shown in Figures 1 and 5. A projection or pin 68 removably secured to and extending outwardly from each end wall of the scraper bowl moves in a path normally occupied by the lowermost arms of the latch members 64 and 66. For the purpose of explanation, assume that the bowl 10 occupies the position shown in Figure 1, wherein the pin 68 carried by the bowl occupies a position between the two lowermost arms of the rotary latch members 64 and 66. Assume further that the valve handle 46 is manipulated so as to cause the actuator piston 34 to be shifted forwardly, namely, to the left. This causes the lowermost arm of the latch member 66 to be moved into engagement with the pin 68. The latch member at that instant is secured against rotation in a counter-clockwise direction, as viewed in Figure 1, through the agency of a shiftable abutment or pawl 70. Thus, the bowl may be shifted in a counter-clockwise direction to the position shown in Figure 3. Simultaneously with the rotation of the bowl, the rocker arm 58 is shifted in a counter-clockwise direction, thereby elevating the trailer wheels 62 and positioning the cutting edge 16a of the bowl in position for digging into the soil. After a load has been acquired by the bowl in response to the forward movement of the draft frame 14, which is pulled by the tractor 44, and it is desired to shift the bowl to the carrying position shown in Figure 4, the valve handle 46 is shifted so as to impart rearward movement to the piston 34, namely, to the right, Figures 1 and 4, thereby bringing the lowermost arm of the latch member 64 into operative engagement with the pin 68. Clockwise rotation of the latch member

64, as viewed in Figure 1, is prevented by means of a shiftable abutment or pawl 72, which is similar in structural characteristics to the previously mentioned pawl 70. Thus, the bowl is not only tilted rearwardly but is elevated from the ground so as to facilitate the ease with which the load may be transferred from one position to another.

Upon reaching a desired point, the load is to be dumped and this is occasioned by again causing the piston 34 to be shifted forwardly, and this time it is permitted to reach the limit of its forward position, thereby causing the pin 74 carried by the latch bar 50 to engage a pivoted lever 76 carried by a bracket 78 on the draft frame 14. The lever 76 is normally secured in its vertical position through the agency of a suitable spring 80. The engagement of the pin 74 with the lever 76 causes cords 82 and 84, connected respectively with levers 86 and 88, to be shifted forwardly. A rod 90 extending between the levers 86 connects with one end of the cord 82, and a similar rod 92 connects with one end of the cord 84. The forward movement of these levers 86 and 88 causes the pawls or abutments 70 and 72 to be shifted out of the path of the arms of the rotary latch members 64 and 66. Thus, the rotary latch members present no obstruction to the movement of the pin 68, and the bowl is free to roll over in response to the pulling action of the draft frame. Springs 70a and 72a associated with the pawls 70 and 72 respectively normally urge said pawls inwardly, so that when the levers 86 and 88 return to their normal vertical position, in response to the return movement of the piston 34, the rotary latch members 64 and 66 are again conditioned for latching the pins 68. This may be more readily understood when it is assumed that, after the bowl has been completely inverted through the pulling action of the tractor and the pin 68 is moved into engagement with the rotary latch member 66, said latch member is free to rotate in a clockwise direction, because the pawl 70 only operates to secure the member 66 against rotation in a counter-clockwise direction. The lever 86 having been returned to its normal vertical position, causes the pawl 72 to be located in position to prevent rotary movement of the member 64 in response to the engagement therewith of the pin 68.

From the foregoing description, it will be apparent that my improved latching and tripping device is so arranged as to enable the pin to be automatically released when it is desired to dump the load, and to become automatically latched after the load has been disposed of, and this is accomplished without raising or lowering latch members of the type which have heretofore been employed.

It will be seen that the stop 74 carried by the actuator bar 50 may be adjusted to various positions, and it will also be noted that the actuator cylinder 72 is pivotally mounted upon the draft frame 14 by means of a bracket carried by the frame. In order to enable the manual manipulation of the tripping or latching mechanism just described, I provide a third cord 96, which extends between the side 48 and the lever 76. By having the link mechanism 56 adjustable to various lengths, I am able to more accurately adjust the positioning of the cutting edge 16a with respect to the position occupied by the trailer wheels. In order to insure the return to the normal vertical position of the levers 86 and 88, I provide springs 86a and 88a, respectively.

Referring now to Figure 6 of the drawings, it will be seen that my invention also contemplates the provision of a modified scraper construction wherein a scraper bowl 10a is positively secured against rotation by means of bolts or rivets 98, which extend through the draft frame 14 and the end wall of the scraper. In the structure shown in Figure 6, I prefer to eliminate the bottom section and also the latch mechanism. Thus, the only parts which are required to cause the proper functioning of the scraper are the actuating bar 50, the cross bar 52, the pivoted frames 54, the extensible link 56, the bell-crank 58, and the trailer wheels 62. Movement of the actuating bar 50 in a rearward direction causes the scraper to be raised, and movement in the opposite direction causes the trailer wheels 62 to be elevated, thereby enabling the scraper to more aggressively engage the surface of the soil.

In Figures 7 and 8 I have disclosed a still further modification wherein I provide a modified mechanism for effecting the raising and lowering of the trailer wheels 62. This mechanism includes an inclined guide 100 secured at each side of the draft frame 14. Slidable within the guide 100 is a block 102 which provides the support for the axle or shaft 60. The blocks 102 are connected through the agency of an extensible link mechanism 56a with the frame 54. The device shown in Figure 7 also includes a modified arrangement of the hydraulic actuator 30. The actuator 30 in Figure 7 is horizontally positioned upon the draft frame 14, and is connected to the frames 54 by means of a piston rod 104 and a link 106, which extends between the free end of the rod 104 and the frame 54. A pin 108 which connects with the link 106 and the rod 104 is slidably guided within a guide block 110 carried by the draft frame 14. In all other respects the structural arrangement of the device shown in Figures 7 and 8 is similar to that already described in connection with Figures 1 to 5, inclusive. Forward movement of the piston 34 in Figure 7 causes the counter-clockwise rotation of the bowl 10, and likewise causes the axle 60 to be elevated, thereby enabling the cutting edge of the bowl to more aggressively dig into the surface of the soil. Upon reverse movement of the piston 34, the axis of the trailer wheels 62 is shifted below the draft frame, thereby, in effect, causing an elevation of the frame to render the bowl, now in its carrying position, more readily transferable from one position to another.

From the foregoing description it will be apparent that my invention contemplates the provision of new and improved structural characteristics which render the use of a trailer type or rotary type scraper more practical in the field. The automatic tripping mechanism eliminates the manual manipulation of a pull rope, and also eliminates the necessity of raising and lowering an actuating bar to effect the proper latching of the bowl. It will also be apparent that my invention permits latching of the bowl in forward and reverse direction with equal effectiveness.

Furthermore, the devices combined with the hydraulic actuator for raising and lowering the bowl, provides a very practical construction. Causing the latching to take place at the opposite ends of the bowl instead of at the limit thereof also presents distinct advantages over prior devices with which I am familiar. Having a latch mechanism positioned at each extremity makes for rigidity and prevents lateral twisting or shifting of the bowl in the event that the load should

be heavier on one side than on the other during its use in the field. Having the latching occur automatically in response to the shifting of the hydraulic actuator also presents advantages which have heretofore, to my knowledge, not been obtainable. Also, having the optional bottom arrangement of the bowl, that is, having the bowl supplied with or without a bottom section, enables a rotary bowl construction to be used with the same degree of effectiveness for the same purpose as a non-rotatable open bottom scraper.

It will be noted in Figure 5 that the pin or projection 68 is removably mounted by means of a nut and bolt construction within the end wall of the bowl structure 10. Thus, when it is desirable to rigidly secure the bowl in fixed position with respect to the draft frame 14 by inserting bolts within the registering apertures 28 and 28a, the pins 68 may be removed so as to permit free movement in either direction of the tiltable arms 54. In other words, the latching mechanism need not be employed and hence the pins 68 may be removed.

While in the drawings I have disclosed specific embodiments of my invention, it will be understood that the invention is by no means limited to these specific forms, but is capable of numerous other changes and modifications without departing from the spirit and scope of the appended claims.

Having thus described my invention, what I claim as new and desire to secure by Letters Patent is:

1. In a scraper adapted to be moved across the surface of the ground, the combination with a rotary earth carrying means having an edge adapted to engage the surface of the soil of means including an actuating member shiftable to cause rotation of the earth carrying means, latch means for controlling the connection of the actuating member with the earth carrying means, and means operable in response to the operation of said actuation member for automatically releasing said latch means to permit free rotation of the earth carrying means.

2. In a scraper adapted to be moved across the surface of the ground, the combination with a rotary earth carrying means having an edge adapted to engage the surface of the soil of means including an actuating member shiftable to cause rotation of the earth carrying means, latch means for controlling the connection of the actuating member with the earth carrying means, and means automatically operable upon operation of said actuating member and said earth carrying means for releasing said latch means to permit free rotation of the earth carrying means in either direction.

3. In a scraper adapted to be moved across the surface of the ground, the combination with a rotary earth carrying means having an edge adapted to engage the surface of the soil of means including an actuating member shiftable to cause rotation of the earth carrying means, latch means for controlling the connection of the actuating member with the earth carrying means, and means operable in response to the shifting of said actuating member for automatically releasing said latch means to permit free rotation of the earth carrying means.

4. In a scraper adapted to be moved across the surface of the ground, the combination with a rotary earth carrying means having an edge adapted to engage the surface of the soil of means including an actuating member shiftable to cause

- rotation of the earth carrying means, latch means for controlling the connection of the actuating member with the earth carrying means, and means operable in response to the operation of said actuating member for automatically releasing said latch means to permit free rotation of the earth carrying means, and means for rendering said latch means again functionally operative to secure the earth carrying means in a pre-determined position.
5. In a scraper adapted to be moved across the surface of the ground, the combination with a rotary earth carrying means having an edge adapted to engage the surface of the soil of means including an actuating member shiftable to cause rotation of the earth carrying means, a hydraulic actuator coupled with said actuating member, latch means for controlling the connection of the actuating member with the earth carrying means, and means operable in response to the shifting of said hydraulic actuator for automatically releasing said latch means to permit free rotation of the earth carrying means.
6. In a scraper adapted to be moved across the surface of the ground, the combination with a rotary earth carrying means having an edge adapted to engage the surface of the soil of means including an actuating member shiftable to cause rotation of the earth carrying means, rotary latch means providing a connecting medium between the actuating member and the earth carrying means, means for securing said rotary latch means against rotation in a given direction, and means for automatically rendering said securing means functionally inoperative to permit free rotation of the earth carrying means.
7. In a scraper adapted to be moved across the surface of the ground, the combination with a rotary earth carrying means having an edge adapted to engage the surface of the soil of means including an actuating member shiftable to cause rotation of the earth carrying means, rotary latch means providing a connecting medium between the actuating member and the earth carrying means, means for securing said rotary latch means against rotation in a given direction, an abutment movable with the rotary earth carrying means and adapted to engage the rotary latch means, and means for automatically rendering said securing means functionally inoperative to enable the abutment of the earth carrying means to move past the rotary latch means.
8. In a scraper adapted to be moved across the surface of the ground, the combination with a rotary earth carrying means having an edge adapted to engage the surface of the soil of means including an actuating member shiftable to cause rotation of the earth carrying means, rotary latch means including a pair of peripherally toothed devices providing a connecting medium between the actuating member and the earth carrying means, means for securing said rotary latch means against rotation in a given direction, and means for rendering said securing means functionally inoperative to permit free rotation of the earth carrying means.
9. In a scraper adapted to be moved across the surface of the ground, a supporting wheel frame, an earth carrying means mounted for rotation about a pivot and having an edge adapted to engage the surface of the soil, said pivot being displaceable vertically with respect to the wheel frame, means including an actuating member shiftable to cause rotation of the earth carrying means and displacement of said pivot, latch means for controlling the connection of the actuating member with the earth carrying means, and means for releasing said latch means to permit free rotation of the earth carrying means.
10. In a scraper adapted to be moved across the surface of the ground, the combination with a rotary earth carrying means having an edge adapted to engage the surface of the soil, said carrying means being bodily displaceable with respect to the ground level, of means including an actuating member shiftable to cause rotation of the earth carrying means and to cause the bodily displacement thereof, tilttable frame members positioned at each end of the rotary earth carrying means, a latch mechanism carried by each tilttable frame member for controlling the connection between the actuating member and said earth carrying means, abutments positioned at each end of and movable with the rotary earth carrying means and adapted to cooperate with the latch means for securing the earth carrying means in a predetermined position with respect to the frame, and means for controlling the functioning of said latch means.
11. In a scraper adapted to be moved across the surface of the ground, the combination with a rotary earth carrying means having an edge adapted to engage the surface of the soil of means including an actuating member shiftable to cause rotation of the earth carrying means, tilttable frame members positioned at each end of the rotary earth carrying means, co-operating pairs of rotary latch wheels carried by said tilttable frame member for controlling the connection between the actuating member and said earth carrying means, abutments positioned at each end of and movable with the rotary earth carrying means and adapted to cooperate with the latch wheels for securing the earth carrying means in a predetermined position with respect to the frame, and means for controlling the functioning of said latch means.
12. In a scraper adapted to be moved across the surface of the ground, the combination with a rotary earth carrying means having an edge adapted to engage the surface of the soil of means including an actuating member shiftable to cause rotation of the earth carrying means, tilttable frame members positioned at each end of the rotary earth carrying means, a latch mechanism carried by said tilttable frame member, abutments positioned at each end of and movable with the rotary earth carrying means and adapted to cooperate with the latch means for securing the earth carrying means in a predetermined position with respect to the frame, means for controlling the functioning of said latch means, said actuating member being positioned intermediate said tilttable frames and connected therewith, a hydraulic actuator including a relatively shiftable cylinder and piston construction coupled with said actuating member, and a pivotal support for said hydraulic actuator.
13. In a scraper adapted to be moved across the surface of the ground, the combination with a rotary earth carrying means having an edge adapted to engage the surface of the soil of means including an actuating member shiftable to cause rotation of the earth carrying means, latch means for controlling the connection of the actuating member with the earth carrying means, means for controlling the functioning of said latch means, a draft frame providing a

mounting for the rotary earth carrying means, and securing means for securing said earth carrying means together with said draft frame as a unit when it is not necessary to rotate said 5 earth carrying means.

14. In a scraper adapted to be moved across the surface of the ground, an earth shifting means having an edge adapted to engage the surface of the soil, a draft frame providing a mounting for 10 said earth shifting means, a tiltable actuating device supported by said frame, a trailer positioned to the rear of said earth shifting means, said actuating means being supported independently of said trailer, means operable in response 15 to the tilting of said actuating means for varying the position of the trailer with respect to the earth shifting means so as to vary the position of said edge with respect to the surface of the soil, and power means for shifting said actuating 20 means.

15. In a scraper adapted to be moved across the surface of the ground, an earth shifting means having an edge adapted to engage the surface of the soil, a draft frame providing a mounting for 25 said earth shifting means, a tiltable actuating device supported by said frame, a trailer positioned to the rear of said earth shifting means, said actuating means being supported independently of said trailer, means including a device 30 pivotally supported by the frame and operable in response to the tilting of said actuating means for varying the position of the trailer with respect to the earth shifting means so as to vary the position of said edge with respect to the 35 surface of the soil, and power means for shifting said actuating means.

16. In a scraper adapted to be moved across the surface of the ground, an earth shifting means having an edge adapted to engage the surface of 40 the soil, a draft frame providing a mounting for said earth shifting means, a tiltable actuating device supported by said frame, a trailer positioned to the rear of said earth shifting means, said actuating means being supported independently 45 of said trailer, means including a guide rigidly secured to the frame and a slide therein operable in response to the tilting of said actuating means for varying the position of the trailer with respect to the earth shifting means so as to vary 50 the position of said edge with respect to the surface of the soil, and power means for shifting said actuating means.

17. In a scraper adapted to be moved across the surface of the ground, an earth shifting means 55 having an edge adapted to engage the surface of the soil, a draft frame providing a mounting for said earth shifting means, a tiltable actuating device supported by said frame, a trailer positioned to the rear of said earth shifting means, 60 said actuating means being supported independently of said trailer, adjustable means operable in response to the tilting of said actuating means for varying the position of the trailer with respect to the earth shifting means so as to vary the 65 position of said edge with respect to the surface of

the soil, and power means for shifting said actuating means.

18. In a scraper adapted to be moved across the surface of the ground, a rotary earth carrying means having a detachable bottom section provided with an edge adapted to engage the surface of the soil, a draft frame for pivotally supporting said earth carrying means, said rotary earth carrying means also including an outer arcuate section, an inner arcuate section spaced therefrom, 10 and strut members extending between said sections whereby to present a rigid scraper structure, means including an actuating member shiftable to cause rotation of the earth carrying means, 15 latch means for controlling the connection of the actuating member with the earth carrying means, and means for controlling the functioning of said latch means.

19. In a scraper adapted to be moved across the surface of the ground, a frame member having 20 a portion adapted to be shifted toward and away from the ground level, rotary earth carrying means pivotally mounted on said frame member portion, means for shifting said portion, 25 means for rotating said earth carrying means, and means connecting said shifting and rotating means for simultaneous operation.

20. In a scraper adapted to be moved across the surface of the ground, a frame member having 30 a portion adapted to be shifted toward and away from the ground level, rotary earth carrying means pivotally mounted on said frame member, means for shifting said portion, means for 35 rotating said earth carrying means, means connecting said shifting and rotating means for simultaneous operation, and means for releasing said connecting means to permit independent rotation of said earth carrying means.

21. In a scraper adapted to be moved across the surface of the ground, a rotary earth carrying means bodily displaceable with respect to the ground level and having an edge adapted to engage the surface of the ground, means including 40 an actuating member shiftable to cause bodily displacement of the earth carrying means, latch 45 means for controlling the connection of the actuating member with the earth carrying means, and means operable in response to the operation of said actuating member for automatically releasing 50 said latch means to permit free rotation of the earth carrying means.

22. In a scraper adapted to be moved across the surface of the ground, a rotary earth carrying means bodily displaceable with respect to the ground level and having an edge adapted to engage the surface of the ground, means including 55 an actuating member shiftable to cause controlled rotary movement and bodily displacement of the earth carrying means, latch means for controlling the connection of the actuating member with the 60 earth carrying means, and means operable in response to the operation of said actuating member for automatically releasing said latch means to permit free rotation of the earth carrying means.

RAYMOND L. HARRISON.
